BY Chas. C. Gill
ATTORNEY.

UNITED STATES PATENT OFFICE.

CHARLES EDWARD HAVILAND, OF LIMOGES, FRANCE.

DESIGN FOR A COVERED DISH.

SPECIFICATION forming part of Design No. 24,171, dated April 2, 1895.

Application filed December 13, 1894. Serial No. 531,731. Term of patent 7 years.

To all whom it may concern:

Be it known that I, CHARLES EDWARD HAVILAND, a citizen of the United States, residing at the city of Limoges, in the Republic of France, have invented and produced a new and original Design for a Covered Dish, of which the following is a specification, reference being had to the accompanying drawings, forming part thereof, in which—

10 Figure 1 is a top view of a covered dish bearing my design. Fig. 2 is a side elevation of same; and Fig. 3 is a detached sectional view through a portion of same on the dotted line 3—3 of Fig. 1.

15 The leading features of my design consist in the ornamental form and configuration of the body of the dish and its cover and the ornate scroll work displayed thereon, as shown in the drawings forming a part of this application.

20 In the drawings A designates the body of the dish and B the cover therefor, the said cover having a raised center bearing a handle C and at its edges formed with the scalloped sections D, E, the latter being smaller than and intermediate of the sections D. Upon the cover B at suitable intervals are the scrolls F, G, H, the scrolls F being edge scrolls and in relief, the scrolls G being curved inward 25 from the edge of the cover and in relief, and the scrolls H being in intaglio and extending on curved lines outward from the scrolls G, as illustrated more clearly in Fig. 1.

The raised central portion of the cover in-

clines downward and outward and merges 35 into the outer portions of the cover on a practically imperceptible line.

The body A projects outward along the central portion of its sides and has at opposite ends the handles I. The outwardly projecting portion of the sides of the body A forms 40 a distinctive feature, and, as shown, said portion extends outward beyond the vertical plane of the upper edges of the dish. From the outwardly projecting portion of the sides 45 of the body A the said sides turn rather abruptly inward and downward to meet the base J and gracefully turn inward and upward to meet the upper edges of the dish. The sides of the body A terminate in a base J and are 50 formed with scalloped sections K, L, corresponding and harmonious with the scalloped sections D, E, along the edge of the cover B.

Upon the sides of the body of the dish are the ornamental scrolls M, N, O, which are reproductions of the scrolls F, G, H, displayed 55 upon the top of the cover B.

What I claim is—

The design for a covered dish, substantially as shown and described.

Signed at the city of Limoges, in the Republic of France, this 23d day of November, 60 A. D. 1894.

CHARLES EDWARD HAVILAND.
